UNITED STATES PATENT OFFICE.

GEORG ERICH DIETZEL, OF DUSSELDORF, GERMANY, ASSIGNOR TO RHEINISCHE METALLWAAREN- UND MASCHINENFABRIK, OF DUSSELDORF - DERENDORF, GERMANY.

MECHANISM FOR AUTOMATICALLY FIRING GUNS.

1,054,514.

Specification of Letters Patent. Patented Feb. 25, 1913.

Application filed November 14, 1910. Serial No. 592,304.

To all whom it may concern:

Be it known that I, GEORG ERICH DIETZEL, engineer, a subject of the German Emperor, residing at 59 Jülicherstrasse, Dusseldorf, 5 Germany, have invented certain new and useful Improvements in Mechanism for Automatically Firing Guns; and I do hereby declare the following to be a full, clear, and exact description of the invention, such as 10 will enable others skilled in the art to which it appertains to make and use the same.

This invention relates to mechanism for automatically firing a gun by the act of closing the breech; and the object of the 15 invention is to provide simple and highly efficient means which will prevent such firing until the breech has been completely closed.

The invention will be hereinafter fully 20 set forth and particularly pointed out in the claims.

In the accompanying drawings Figure 1 is a side elevation of the breech end of a 25 gun barrel having a breech block according to the invention. Fig. 2 is a plan, and Figs. 3 and 3^a show a detail.

In the example shown, the breech block is of the wedge shaped kind operated by a cranked handle. The breech block lever has 30 two arms and is pivoted on a pin *b* in the breech end *a* of the barrel; one arm *c* of this lever, termed hereinafter the angle arm, carries a pivoted block *d* which, when the lever is turned, slides in a groove *e* in the 35 breech block *f* and thus opens or closes the breech. Instead of the block *d* any suitable form of pin can be used. The second arm of the breech block lever is made up of two 40 lever arms *g* and *h* coupled together. The arm *g* turns on the pin *b*, while arm *h* carries the handle *i*. The connection between 45 these arms consists of a pin *k* on arm *h* provided with one part of a bayonet joint and engaging with the other part of the bayonet joint which is in a cavity of arm *g*. In arm *g* there is a pin *m* normally pressed by a 50 spring *n* into a corresponding cavity in arm *h* (see also Fig. 3), and thus preventing a relative movement between arms *g* and *h*. The spring pin *m* has a projection *o* in 55 which is an inclined groove *p*. When the breech block lever is near the end of its movement a pin *q* on the breech end *a* of the gun engages in the groove *p*, and on fur-

ther movement of the lever compresses the 55 spring pin *m* so that at the moment when the breech is completely closed, this coupling between the two arms *g* and *h* is released. The handle *i* can now be moved farther toward the barrel whereupon arm *h* swings 60 away from arm *g*. The arm *h* strikes against a rod *r* connected with a bell crank lever *s* pivoted in the breech end *a*. When the breech is closed, this lever *s* is adapted to engage with a lever *t* arranged in the 65 breech block *f*. The turning of the lever *t* actuates the firing pin arranged in the breech block *f* in known manner. The firing pin is therefore actuated as soon as, after the breech is closed, the arm *g* of the breech block lever 70 comes to rest, and the arm *h* has been moved farther toward the barrel by handle *i*.

In the above described construction it is possible that the coupling pin *m* between the arms *g* and *h* might be released too soon. 75 The shot would then be fired before the breech was closed and the breech block might be blown off. An accurately acting lock for preventing firing until the breech is completely closed is therefore required. 80 For this purpose the bell crank lever *s* has an arm *u* which moves into the path of the block *d*. The length of arm *u* is such that it cannot swing past the block *d* until the latter has arrived at its final position, that 85 is, until the breech is completely closed. The advantage of this lock is that the block *d* is used as a locking means which toward the end of the closing motion arrives at or nearly at the dead position of the angle arm, that is traverses a fairly considerable distance while the breech block makes no or only a very small movement. The same result may be obtained if instead of the sliding block *d* a fixed pin is employed to move 90 the breech block and in like manner lock the firing pin.

Having now particularly described and ascertained the nature of my said invention and in what manner the same is to be performed I declare that what I claim is:

1. The combination with a gun barrel having a breech block and a firing pin, of a lever for actuating the breech block comprising two parts movable on planes parallel to the plane of movement of the breech block, means for holding said parts in fixed relation to each other while moving the 105

breech block to a closed position, and means for acting on such last mentioned means in closing the breech permitting one of said parts to be further moved in the same direction as in its initial movement, but independently of its complementary part, as the breech is closed, to actuate the firing pin.

2. The combination with a gun barrel 10 having a breech block, and a firing pin, of a lever for actuating the breech block comprising two parts movable on planes paralleling the plane of movement of the breech block, means for holding such parts in fixed 15 relation to each other while moving the breech block to closed position, and means for automatically releasing said holding means, as the breech is being closed, to permit of one of said parts to be further moved 20 in the same direction as in its initial movement with its complementary part but independently thereof to actuate the firing pin.

3. The combination with a gun barrel having a breech block and a firing pin, of a 25 lever for actuating the breech block comprising two parts, a coupling pin for holding such parts in fixed relation to each other while moving the breech block to closed position, and means for automatically dis-

engaging said pin from one of said parts, as 30 the breech is being closed, to permit such part to be further moved in the same direction as its initial movement with its complementary part but independently thereof, to actuate the firing pin. 35

4. The combination with a gun barrel having a breech block, and a firing pin, of a lever for actuating the breech block, comprising two parts, a spring pressed coupling pin mounted on one of said parts and 40 designed to engage the other part to hold both parts in fixed relation to each other while the breech block is being moved to closed position, said pin having a diagonally arranged groove, and a fixed part 45 for engaging said groove to move the spring-pressed pin in opposition to its spring to permit one of said parts to be moved independently of the other part to actuate the firing pin. 50

In testimony whereof, I have signed this specification in the presence of two subscribing witnesses.
